UNITED STATES PATENT OFFICE.

WILLIAM K. HERRINGTON, OF AURORA, ILLINOIS.

DESIGN FOR A CUFF-HOLDER.

SPECIFICATION forming part of Design No. 31,548, dated September 26, 1899.

Application filed August 14, 1899. Serial No. 727,223. Term of patent 7 years.

To all whom it may concern:

Be it known that I, WILLIAM K. HERRINGTON, a citizen of the United States, residing at Aurora, in the county of Kane and State 5 of Illinois, have invented and produced a new and original Design for Cuff-Holders, of which the following is a specification, reference being had to the accompanying drawings, forming a part of this application, and in which—

10 Figure 1 is a perspective view of a cuff-holder, showing my original design. Fig. 2 is a side edge elevation of said cuff-holder. Fig. 3 is a top plan view showing one side of the cuff-holder. Fig. 4 is a cross-sectional view 15 on the line 4 4 of Fig. 3.

As shown in the drawings, the leading or material feature of my design consists of a generally S-shaped figure with flattened ends, which is distinguished by its peculiar 20 configuration. This figure comprises, substantially, a body A, oblong in shape, and

two arms B B, connected with the body by a curved bend C and extending inward toward each other close to the body and on opposite sides thereof, with the extreme ends D curved 25 or turned slightly upward. At the bend forming the juncture of the arms with the body the holder is wider than elsewhere, as shown in Fig. 3, and longitudinal ribs E are stamped or otherwise formed on the arms and 30 on the body beneath the arms, as shown in Fig. 2.

Having thus fully described my invention, what I claim, and desire to secure by Letters Patent, is—

35 The design for a cuff-holder, substantially as herein shown and described.

WILLIAM K. HERRINGTON.
